UNITED STATES PATENT OFFICE.

JOHN W. PEPPLE, OF HILLSBORO, TEXAS.

BURIAL-VAULT.

980,670.

Specification of Letters Patent.

Patented Jan. 3, 1911.

Application filed December 28, 1909. Serial No. 535,234.

To all whom it may concern:

Be it known that I, JOHN W. PEPPLE, a citizen of the United States, residing at Hillsboro, in the county of Hill and State 5 of Texas, have invented new and useful Improvements in Burial-Vaults, of which the following is a specification.

The present invention is an improvement in burial vaults, and its primary object, 10 stated broadly, comprehends the production of a vault so constructed as to be rendered perfectly air and moisture proof when closed and sealed.

As a secondary object, the invention includes the production of simple and effective 15 means for exhausting noxious gases from the interior of the vault, and the further production of means for protecting the afore-mentioned exhausting means.

More especially, the invention resides in 20 the particular construction of the two component parts of the vault, namely, the top and bottom sections thereof; in the particular form of seal or joint made use of; and in 25 the particular exhausting means employed and its associated protecting means.

A structural embodiment of the invention is illustrated in the accompanying drawings, 30 wherein—

Figure 1 is a perspective view of the vault, with its top section raised; Fig. 2 is a 35 transverse vertical section of Fig. 1; Fig. 3 is a sectional view showing the closed vault in position in the ground, and the exhausting and protecting means in position.

As shown in said drawings, the vault is composed of top and bottom sections 1 and 2, constructed of concrete or other suitable material. The bottom section comprises 40 side and end walls, 3, 3 and 4, 4, and a floor, base, or bottom wall 5, its top being open. In the upper face of said side and end walls, there is formed a continuous depression or seat 6, having in its outer wall intermediate 45 the upper and lower edges thereof, a groove 7, which is likewise continuous.

In the construction shown, the top section has its side walls 8, 8 sloping or converging, so as to shed any water which may 50 reach the same after percolating through the ground. This section is formed at its edge portion with a continuous depending flange 10 which conforms to the shape of the seat 6, wherein it is designed to be received, and 55 is provided in its outer face with a con-

tinuous groove 11, said groove alining with groove 7 when said section is in place. The thickness of the flange is appreciably less than the width of seat 6, and its dimensions are such that its inner face will fit squarely 60 against the inner wall of said seat, so as to completely close the interior of the vault. Toward its lower edge the flange tapers slightly, the faces thereof sloping inwardly, as shown, and at said edge there is formed a 65 series of depending spaced projections 12 which are adapted to rest upon the bottom wall of the above mentioned seat and thus support the top section in position.

There are provided upon the top section 70 lateral projections 13 which in the present instance are shown as formed upon the end walls 9, 9, of said section. At their necks, i. e., the points where they join said end walls 9, 9, said projections are slightly undercut as indicated by the numeral 14. These projections 13 constitute supports to which the ropes, (not shown), for raising and lowering said section may be attached, the undercutting 14 preventing the ropes 80 from slipping during such operation. Means is also provided for supporting the bottom wall of the vault slightly above the bottom of the grave after said vault has been lowered thereinto, so as to permit the 85 withdrawal of the ropes by means of which that operation is effected. Such means may be in the nature of spaced ribs 15 formed upon the lower face of the vault bottom.

The gas-exhausting means afore-men- 90 tioned is shown in the present instance as constituted by a vertically-arranged pipe 16, preferably constructed of copper, one end of which is received in an opening 17 formed through one of the walls of the top section, 95 while its other end is covered by an inverted earthenware receptacle 18, said pipe extending upwardly to a point not far removed from the surface of the ground, as shown in Fig. 3. It will thus be seen that the ex- 100 haust pipe will conduct from the interior of the vault all gases which may emanate from the casket 19 therewithin, while the arrangement of the receptacle above the outlet end of said pipe will serve to protect the latter by preventing the entrance of dirt or moisture thereinto.

In order to render the vault perfectly air and moisture proof, a seal or joint between the two sections thereof is employed. This 110

seal, which is of a composite nature, consists essentially of a lower part or layer 20 of pitch, and an upper layer 21 of concrete or other cementitious material. The method 5 of constructing said seal is as follows, it being understood of course, that the vault is sealed subsequent to the disposition of the casket within its interior: Hot pitch is poured into seat 6, and the top section 1 of 10 the vault then placed in position upon the lower section, with its flange 10 extending into said seat and its projections 12 resting on the bottom wall thereof. The entry of 15 the flange into said seat will cause the pitch to ascend on both sides thereof, this being facilitated by the inclined faces of said flange and by the spaced arrangement of 20 said projections. To these faces, as well as to the opposite walls of the seat, the pitch readily adheres, thereby forming a permanent air and moisture proof seal, as will be understood. When this operation has been completed, the remainder of the seat is filled 25 with cement mortar, which is just thick enough to admit of its being worked with a trowel. This layer or filling of cement enters and fills the alining grooves 7 and 11, thereby forming keys or locks which, when hardened, positively preclude subsequent 30 removal of the top section; said layer also serves to protect the above mentioned seal from exposure to the elements. The cement also fills that portion of the seat which is above said grooves, as well as the space between 35 the side and end edges of the top section and the corresponding outer edges of the bottom section, as shown, the upper face of the cement being subsequently pointed off with the trowel. At the completion of the 40 formation of the joint, the vault is lowered into the grave in the usual manner by means of ropes which may be withdrawn after the vault is in position, owing to the formation of the ribs 15, or their equivalents. The 45 exhaust pipe is then attached to the top section of the vault, after which the grave is filled in almost to the upper end of said pipe. The vessel or receptacle 18 is then placed over said pipe end, and the filling in 50 of the grave finally completed.

I claim as my invention:

1. A burial vault comprising a bottom section formed at its upper face with a continuous seat; a top section formed with a continuous flange extending into said seat, 55 said flange having the lower portion of its inner face sloping away from the inner wall of said seat to provide a space between said wall and face, and its lower edge formed with a series of spaced projections adapted 60 to rest upon the bottom wall of said seat for supporting said top section in position; and a composite grout consisting of a layer of non-cementitious material filling the lower portion of the seat and extending through 65 the spaces between said projections into the space between said sloping face and the inner wall of said seat to constitute a permanent air- and moisture-proof seal between 70 said sections, and a layer of cementitious material filling the upper portion of said seat to constitute a permanent lock between said sections and to protect said seal from exposure to the elements.

2. A burial vault comprising a bottom section having a continuous seat formed in its upper face; a top section having a continuous depending flange extending into said seat, said flange having the lower portion of its opposite faces arranged in spaced relation to the adjacent walls of said seat, and its lower edge formed with depending projections adapted to rest upon the bottom wall of said seat to support said top section in position and spaced apart to provide means 85 of communication between the spaces at opposite sides of said flange; and a grout filling said seat and extending upon both sides of said flange through the spaces between 90 said projections into contact with both faces of said flange and both walls of said seat, to constitute a permanent lock between said sections.

In testimony whereof I have hereunto set my hand in presence of two subscribing witnesses.

JOHN W. PEPPLE.
